UNITED STATES PATENT OFFICE.

IRA MCCLURE, OF MARION, INDIANA.

DISH-WASHER.

1,036,669.

Specification of Letters Patent. Patented Aug. 27, 1912.

Application filed October 14, 1911. Serial No. 654,712.

To all whom it may concern:

Be it known that I, IRA MCCLURE, a citizen of the United States, residing at Marion, in the county of Grant and State of Indiana, have invented a new and useful Dish-Washer, of which the following is a specification.

This invention pertains to improvements in what may be termed dish washers.

10 The invention has for its object to provide for expeditiously and effectively washing or cleansing the dishes.

A further object is to provide for suitably supplying the suds-water to the dishes and 15 water for rinsing the dishes after the washing operation proper.

A still further object is to provide for suitably directing the action of the water upon the dishes in effecting the cleansing 20 operation.

A still further object is to carry out the aforesaid ends in a simple, economical and effective manner.

The invention consists of certain instrumentalities and features substantially as hereinafter fully disclosed and defined by the claims.

In the accompanying drawing, illustrating the preferred embodiment of my invention 30 wherein it will be understood that various changes and modifications may be made as relates to the detailed construction and arrangement of the parts without departing from the spirit thereof, Figure 1 is a longitudinal section of my dish washing machine. Fig. 2 is an end elevation of the same, parts being broken away. Fig. 3 is an opposite end view thereof. Fig. 4 is a detailed sectional view taken on the line $x-x$ of Fig. 1.

40 Fig. 5 is a further detailed sectional view, showing more especially a bearing of one of the water spraying or jetting pipes. Fig. 6 is a sectional view taken on the line $x-x$ of Fig. 1.

45 In putting my invention into practice, I provide a suitable closure-equipped receptacle 1 for receiving the dishes, the same being preferably provided with a sloping bottom 2 for suitably draining or directing the 50 flow of the water, after use, toward one end thereof, as in withdrawing the water from said receptacle, as will be further explained presently, said receptacle being suitably supported in elevated position by means of suitably attached legs 3, and supplied with a

waste-water cock-equipped outlet 3^a, the cock being designated as 3^b.

Suitably supported to be rocked in their bearings, within the receptacle 1, are a number of pipes 4 provided with numerous perforations 5 in their upper surfaces, through which is delivered or sprayed the water, within the receptacle, upon the dishes. The bearings for the ends of the perforated pipes 4 within the receptacle 1, are comprised of 60 the usual tubular pipe-couplings 6 effecting connection with additional pipe-sections 6^a again referred to, as disclosed especially in Figs. 1 and 2, said couplings being adapted to allow of the rocking or turning of said 70 ends of said pipes therein, as presently explained.

The pipe-sections 6^a effect connection outside of the receptacle 1 with a transverse pipe 7 connected to pump-cylinders 8 for 75 forcing the water through the perforations of the pipes 4 either for primarily washing or cleansing the dishes or for rinsing the latter as presently more fully disclosed. Said pipe 7 has suitably hung therein check 80 valves or gates 7^a to suitably control the intermittent flow of water therethrough under the usual pumping action of the pump pistons, as will be readily appreciated.

In order to provide for rocking or turning 85 the pipes 4, according to the angle of presentation it may be desired to give to the water delivered therethrough, to the dishes being cleansed, said pipes are suitably coupled or connected together and to an upstanding manually actuated lever 9, as clearly disclosed by Figs. 1 and 3. The connection or coupling between the pipes 4 and the lever 9 is effected preferably by suitably socketing or seating laterally as at 10, into 90 the pipes, upstanding bars or members 11 and similarly socketing or seating said lever into one of said pipes and pivotally connecting said upstanding members or bars and said levers together by means of a transverse 100 member or bar 12.

A pump 13, preferably of the force double-cylinder type, and suitably supported in position from, and contiguous to the receptacle 1, has connected to its cylinders 105 14 the pipe 7 above referred to having as stated, connection with the water spraying or supplying pipes 4. The pump 13 also has a three-way cock or valve 15 in a pipe-union or connection 16 between the lower 110

ends of its cylinders 8, which valve is adapted to be suitably actuated manually through its upstanding stem, or member 17 extending upwardly through an adjunctive tubular member 18 of the pump, which may form the fulcrum-member or post of the pump-actuating lever or handle, said stem having preferably attached to its upper end a handle 19 for its convenient actuation, as 10 in operating the cock or valve.

A rinsing-water containing tank 20 is suitably supported contiguous to the pump 13 and has pipe-connection 21 with the valved pipe-connection 16 of the pump 13, 15 oppositely from the point of connection of the suds-chamber connection with said valved pipe connection 16, which suds-chamber connection is effected by means of a pipe 22, establishing communication between 20 said chamber and the pump pipe 16.

The pump-pistons are suitably actuated by a lever or handle 23 fulcrumed intermediate its ends upon the tubular post or member 18 and suitably connected to the piston-rods 24.

A valved, or cock-equipped pipe 25, connected to the pipe 7, uniting the pump-cylinders, is employed for making connection with a further water-supply, in event this 30 may become necessary.

Upstanding preferably tubular or pipe arms 26 are supplied laterally to two intermediate stub-pipes or sections 6*, to afford handholds for the suitable retention thereof 35 against a tendency to turn or partake of the movement of the corresponding water-supplying pipes 4 when it may be desired to disconnect the latter therefrom; as would be done in removing the operative parts of the 40 containing receptacle 1.

A suitable rack or dish-holder upon which the dishes may be suitably and advantageously disposed and supported, as for instance, edgewise and in an inclination with 45 their dished surfaces presented downwardly to receive the cleansing action of the water, comprises a reticulated bottomed member or receptacle 27, its bottom being formed of suitable meshed wire-screen material 28, 50 and a grate or slatted member 29 suitably supported by brackets or otherwise upon the inner surfaces of the lateral portions of the member 27, a short interval above the bottom 28, the slatted member receiving the 55 dishes edgewise between its slats to allow

the dishes to rest at their edges upon said reticulated or meshed bottom. The dish holder and drainer, thus provided is secured within the receptacle 1, directly over the water-supplying or spraying pipes 4. It will 60 therefore be seen that, with the dishes disposed edgewise within the dish-holder and a suitable quantity of soaped water, forming suds placed in the receptacle 1, by suitably actuating the pump as above indicated, the 65 pump-valve 15, in that instance, being adjusted to allow the suds-water to pass therethrough, such water will, by the pumping action, be forced into and sprayed through the pipes 4 upon the dishes for effecting the 70 cleansing of the dishes. The cleansing operation proper having thus been effected, the valve 15 is suitably adjusted or shifted to take the water from the rinsing-water chamber 20, such adjustment of the valve 75 also shutting off communication with the suds-chamber, by now resuming the pumping action the rinsing water will be delivered into the pipes 4 and be sprayed therethrough upon the dishes, thus providing for 80 the thorough or effective cleansing of the dishes. During the primary washing and rinsing operations, the water is thrown upon the dishes in one direction and then in another by suitably actuating the lever 9, 85 which, of course, will aid such cleansing action.

What is claimed is:—

The combination of a receptacle having a suds-water chamber therein, a pump arranged exteriorly of said receptacle, a spraying pipe within said receptacle, a valved pipe-connection between the pump cylinders, said spraying pipe communicating with said valved pipe-connection, a rinsing-water chamber, a second valved pipe-connection between the pump-cylinders, a pipe establishing communication between said second valved pipe-connection and said rinsing water-chamber, and a third pipe-connection between said second valved pipe connection of the pump-cylinders and said suds-water chamber.

In testimony that I claim the foregoing as my own, I have hereto affixed my signature in the presence of two witnesses.

IRA MCCLURE.
